UNITED STATES PATENT OFFICE.

ELLA NEILSON GAILLARD, OF NEW YORK, N. Y.

HOOK AND EYE.

1,340,334.

Specification of Letters Patent.

Patented May 18, 1920.

Application filed February 1, 1919, Serial No. 274,505. Renewed October 4, 1919. Serial No. 328,587.

To all whom it may concern:

Be it known that I, (Mrs.) ELLA NEILSON GAILLARD, a citizen of the United States, and a resident of New York, in the county of 5 New York and State of New York, have invented new and useful Improvements in Hooks and Eyes, of which the following is a specification.

This invention relates to hooks and eyes 10 of the type particularly adapted to be used in connection with wearing apparel and has for its primary object the provision of means whereby the adjacent or adjoining edges of a garment may be easily joined and 15 securely retained in an adjoined relation.

A further object of the invention is to provide a hook and eye of the above mentioned character which is strong, durable, reliable in operation and inexpensive to 20 manufacture.

Other objects and advantages of the invention will be apparent during the course of the following description taken in connection with the accompanying drawings.

25 In the drawings, forming a part of this specification wherein like numerals are employed to designate like parts throughout the same,

Figure 1 is a top plan view of a hook 30 and eye embodying my invention, the same being shown as connected with the adjacent edges of portions of a garment with which it is particularly adapted to be used,

Fig. 2 is a longitudinal sectional view 35 taken on line 2—2 of Fig. 1,

Fig. 3 is a perspective view of a female member,

Fig. 4 is a perspective view of a male member, and,

40 Fig. 5 is a view similar to that of Fig. 2 showing a slightly modified form of the invention.

In the drawings, wherein for the purpose 45 of illustration is shown a preferred form of my invention, the numerals 5 and 6 indicate portions of a garment with which the device embodying my invention is particularly adapted to be used. While I have shown one complete unit as applied to the above 50 mentioned portions of a garment it is to be understood that the construction of the several units which may be employed in cases where a single unit will not suffice are to be substantially identical with the structure 55 hereinafter described.

By the term unit as employed above I

mean the combination of a female member 7 with a male member 8, the female and male members being shown as connected respectively with the portions 5 and 6 in Fig. 1. 60 The female member 7 comprises an elongated bar 9 having arms 10 secured at the ends thereof. The arms 10 are provided with eyelets 11 through which the threads 12 are passed to secure the member as a 65 whole upon the portion 5 of the garment as shown in Fig. 1. Intermediate the ends of the bar 9 there is provided a loop 13, which loop is preferably formed integral with the bar 9 as clearly shown. The male member 70 indicated as a whole by the numeral 8 comprises a bar 9' having arms 10' which are provided with eyelets 11' through which threads 12' are passed in order to secure the member 8 as a whole upon the portion 6 of 75 the garment as clearly shown in Fig. 1. To the bar 9' intermediate its ends there is secured a tongue 14 which is bent rearwardly upon itself as shown at 15. The rearwardly bent portion 15 is then bent substantially 80 upon itself to provide a second tongue 16 which is spaced from the rearwardly bent portion 15 as clearly shown.

In use, the loop 13 is hooked over the tongue 14 whereupon it is confined between 85 the tongue 16 and the rearwardly bent portion 15 as clearly shown in Figs. 1 and 2.

In considering the modified form of my invention shown in Fig. 5 it will be understood that the construction of the same is 90 substantially that of the hereinbefore described members 7 and 8 but instead of employing the form of tongue 16 of Fig. 4 I desire to slightly modify this by forming at the jointure of the tongue 16 and the rear- 95 wardly bent portion 15 a depression 17, which depression is adapted to receive the loop 13, which loop is, instead of being formed flat as shown in Fig. 3, slightly bent at 18 and 19.

100 The operation of the device shown in Fig. 5 is substantially identical with the device hereinbefore described but by bending the tongue 16 to provide the depression 17 and by bending the loop 13 as shown at 18 and 19 the tongue 14 together with the rearwardly bent portion 15 is moved to the dotted line position shown in Fig. 5 when the adjacent edges of the portions 5 and 6 of the garment tend to separate as is readily 110 apparent from the drawings.

It is to be understood that the forms of

my invention herewith shown and described are to be taken as preferred examples of the same, and that various changes in the shape, size and arrangement of parts may be resorted to without departing from the spirit of the invention or the scope of the appended claims.

Having thus described my invention, what I claim as new and desire to secure and protect by Letters Patent of the United States, is:

- 15 1. A hook and eye comprising male and female members, the female member being provided with a loop, the male member being provided with a tongue bent rearwardly upon itself, said tongue and rearwardly bent portion being adapted to enter said loop, and a second tongue carried by the rearwardly bent portion and spaced therefrom.
- 20 2. A hook and eye comprising female and male members, the female member comprising an elongated bar adapted to be secured to a garment, a loop formed integral with

said bar, the male member comprising an elongated bar adapted to be secured to a 25 garment, a tongue formed integral with the bar of the male member, said tongue being bent rearwardly upon itself, said tongue and rearwardly bent portion being adapted to enter said loop, a second tongue secured to 30 the rearwardly bent portion and spaced therefrom, the second named tongue being adapted to engage the surface of the garment.

3. A hook and eye comprising a female 35 member having a loop, a male member comprising an elongated bar, a tongue formed integral with said bar and bent rearwardly upon itself, a second tongue carried by the rearwardly bent portion, the second named 40 tongue being provided with a depression at the jointure of the rearwardly bent portion and the second named tongue, said loop being adapted to be confined within said depression.

ELLA NEILSON GAILLARD.
